(57) **CLAIM**

The ornamental design for a bee cage, as shown and described.

DESCRIPTION

FIG. 1 is a perspective view of a bee cage in an assembled state.

FIG. 2 is another perspective view of the bee cage in the assembled state.

FIG. 3 is a front view of the bee cage of FIG. 1.

FIG. 4 is a rear view of the bee cage of FIG. 1.

FIG. 5 is a side view of the bee cage of FIG. 1.

FIG. 6 is an opposite side view of the bee cage of FIG. 1.

FIG. 7 is a top view of the bee cage of FIG. 1.

FIG. 8 is a bottom side view of the bee cage of FIG. 1.

FIG. 9 is a perspective view of the bee cage in a disassembled state.

FIG. 10 is another perspective view of the bee cage in the disassembled state.

FIG. 11 is a front view of the bee cage of FIG. 9.

FIG. 12 is a rear view of the bee cage of FIG. 9.

FIG. 13 is a side view of the bee cage of FIG. 9.

FIG. 14 is an opposite side view of the bee cage of FIG. 9.

FIG. 15 is a top view of the bee cage of FIG. 9; and,

FIG. 16 is a bottom side view of the bee cage of FIG. 9.
